(57) **CLAIM**

The ornamental design for a hair styling device, as shown and described.

DESCRIPTION

FIG. 1 is a perspective view of a hair styling device showing the inventive design.

FIG. 2 is a second perspective view of said hair styling device showing the inventive design.

FIG. 3 is a front view of said hair styling device showing the inventive design.

FIG. 4 is a rear view of said hair styling device showing the inventive design.

FIG. 5 is a left side view of said hair styling device showing the inventive design.

FIG. 6 is a right side view of said hair styling device showing the inventive design.

FIG. 7 is a top view of said hair styling device showing the inventive design.

FIG. 8 is a bottom view of said hair styling device showing the inventive design; and,

FIG. 9 is a detail view of said hair styling device showing the inventive design.

The broken lines in the figures are for the purpose of illustrating portions of the hair styling device, and form no part of the claimed design. The dot-dash broken lines depict the boundaries of the enlargements and form no part of the claimed design.

1 Claim, 9 Drawing Sheets
